UNITED STATES PATENT OFFICE.

WILLIAM MORRONE, OF PITTSBURGH, PENNSYLVANIA, ASSIGNOR OF ONE-HALF TO
NICOLA MORRONE, OF PITTSBURGH, PENNSYLVANIA.

STREET-INDICATOR.

1,149,392.

Specification of Letters Patent. Patented Aug. 10, 1915.

Application filed August 29, 1914. Serial No. 859,222.

To all whom it may concern:

Be it known that I, WILLIAM MORRONE, a citizen of the United States, residing at Pittsburgh, in the county of Allegheny and 5 State of Pennsylvania, have invented certain new and useful Improvements in Street-Indicators; and I do hereby declare the following to be a full, clear, and exact description of the invention, such as will enable 10 others skilled in the art to which it appertains to make and use the same.

This invention comprehends certain new and useful improvements in street indicators for street cars and the like and has for its 15 primary object to provide an indicator of this character which will be of such construction that the operative parts will be automatically carried back to normal position by means of the weights after each operation of the device.

The invention has for a further object to provide a street indicator of this character which is of extremely simple construction and operation as well as highly efficient in 20 use.

With the above and other objects in view as will become more apparent as the description proceeds, the invention consists in certain novel features of construction, combination and arrangement of parts as will 30 be hereinafter more fully described and claimed.

For a complete understanding of my invention, reference is to be had to the following description and accompanying drawings, in which—

Figure 1 is a front view of the complete device, Fig. 2 is a side view thereof, Fig. 3 is a transverse vertical section on the plane 40 of line 3—3 of Fig. 1, Fig. 4 is a fragmentary detail section on the plane of line 4—4 of Fig. 2, and Fig. 5 is a transverse detail section on the plane of line 5—5 of Fig. 4, looking in the direction indicated by the 45 arrow, with the parts slightly enlarged.

Referring more particularly to the drawings in which similar reference characters designate corresponding parts throughout the several views, 1 designates a casing 50 within which are positioned the transverse lower and upper rollers, 2 and 3 respectively, around which rollers 2 and 3 the cloth 4 is engaged and secured, said cloth having the

names of streets or stations located thereon at spaced distances.

55

The lower roller has a crank 5 formed on one end by means of which said roller may be rotated to wind the cloth 4 thereon, said cloth 4 being withdrawn from said roller 2 and wound upon the upper roller 3 by a step 60 rotation imparted to said upper roller 3 by novel mechanism which will be later fully described. As the cloth 4 is wound upon the upper roller 3, the names upon said cloth 4 are brought into position before the 65 transparent member 6 secured in a transverse opening 7 formed in the front face of the casing 1, the edges of the transparent member 6 being secured in the channel 8 formed in the edge of said opening 7, it being understood that strips are secured to the casing 1 upon its front face around the edge 70 of the opening 7, as shown in Fig. 3, over the edges of said transparent member. It 75 will also be understood that the cloth 4 passes over a guide roller 9 positioned transversely in the casing 1 before reaching the roller 3 to properly guide the cloth 4 before the transparent member 6 and also the upper roller 3.

80

The upper roller 3 has one end spaced from the adjacent side of the casing 1, and against this end of the upper roller 3 is secured a spider member 10 by suitable fastening members 11 passed through the legs of 85 said spider member 10 and into the end of the roller 3, a suitable peg 12 extending through the central opening of the spider member 10 and having its head held against the upper roller 3 by means of said spider 90 member 10. To one of the legs of the spider member 10 is pivoted a pawl 13 which has the bent end 14 of a spring member 15 bearing upon the same to retain said pawl 13 in engagement with the teeth of the ratchet 95 wheel 16 which is rotatably mounted upon the peg 12 and secured to the end of the roller section 17, which is also rotatably mounted upon the peg 12. The spring member 15 is secured to the outer face of the upper roller 3, the end bearing upon the pawl 13 being extended around the end of said upper roller 3 and turned at an angle to the same and to the main portion of said spring member 15.

105

The auxiliary roller section 17 is rotatably

engaged in the bearing sleeve 18, which rests in a suitable bearing opening 19 in the end of the casing 1 or side thereof, the portion of said end or side above the opening 19 and 5 designated by the numeral 1', being slidably engaged between the front and rear walls of the casing 1 in order that the bearing sleeve 18 may be readily placed in position or removed, longitudinal movement of the 10 bearing sleeve 18 being prevented by the flange 20 formed around the same and positioned adjacent the inner face of the end or side of the casing through which said sleeve extends, and the sprocket wheel 21 also formed with the sleeve 18 and positioned adjacent the outer face of said end or side of the casing 1. It will be understood that the lower and upper portions of the end or side of the casing have circular 15 bearing members 22 secured to the edges thereof and forming the bearing for the sleeve 18, thereby preventing wearing of the casing by rotation of the sleeve 18.

A sprocket chain 23 is engaged around 20 the sprocket wheel 21 and has a weight 24 secured to one end, which weight is slidably positioned in the guide tube 25 positioned against the end of the casing 1. When it is desired to operate the device to bring the 25 name of the next street or station before the transparent member 6, the chain 23 is pulled to raise the weight 24 and rotate the sprocket wheel 21 and the sleeve 18. The locking key 26 carried by the sprocket wheel 30 21 and engaged in the slot 27 in the reduced outer end 28 of the roller section 17 serves to lock said roller section 17 for rotation with the sleeve 18 and the sprocket wheel 21, thereby causing the ratchet wheel 16 to rotate the upper roller 3 and thereby wind 35 the cloth 4 upon said roller 3 to bring the next station name before the transparent member 6, the rotation of the upper roller 3 being caused by engagement of the pawl 30 40 45 50 55 21 with said ratchet wheel 16, and as soon as the sprocket chain 23 is released, the weight 24 will descend into the guide tube 25 and thereby cause a reverse rotation of the sleeve 18 and parts carried thereby, without causing a reverse rotation of the upper roller 3, as the ratchet wheel 16 will ride under the pawl 13. When it is desired to rewind the cloth 4 onto the lower roller 2, however, the key 26 is removed, thereby permitting rotation of the upper roller 3 and auxiliary roller section 17 and the parts car-

ried by the same, without causing rotation of the sleeve 18 and parts carried by the same.

While the preferred embodiment of the invention has been shown and illustrated, it will be understood that minor changes in the details of construction, combination and arrangement of parts may be made without departing from the spirit and scope of the invention as claimed or sacrificing any of the advantages thereof.

What is claimed is:—

A device of the class described comprising a lower roller, an upper roller formed of a main roller section and an auxiliary roller section in alignment with said main roller section, a spider member secured to one end of said main roller section, a peg extended centrally from and engaged through said spider member, the head of said peg being engaged against the end of said main roller section, said auxiliary roller section having one end mounted loosely upon said peg, a ratchet wheel secured against the inner end of said auxiliary roller section and engaged around said peg, a spring actuated pawl carried by said spider member and engaged with the teeth of said ratchet wheel, a cloth wound upon the lower roller and secured to the upper roller, a casing for said rollers, the auxiliary section of the upper roller having an annular flange formed at its inner end, a sleeve for said auxiliary roller section, said annular flange limiting inward movement of said sleeve upon said auxiliary roller section, said sleeve being engaged through one end of said casing and adapted to rotate within the same, means for locking the sleeve upon said auxiliary roller section, means for preventing outward movement of said sleeve and auxiliary roller section, a sprocket wheel mounted upon said sleeve outwardly of said casing, a chain engaged around said sprocket wheel, a weight mounted upon said chain for rotating said sleeve and upper roller in one direction to wind the cloth upon said upper roller, and means for rewinding said cloth upon said lower roller.

In testimony whereof I affix my signature in presence of two witnesses.

WILLIAM MORRONE.
